CLAIM

The ornamental design for a bifurcated bent tube, as shown and described.

DESCRIPTION

FIG. 1 is a perspective view of a bifurcated bent tube showing our new design;
FIG. 2 is a front view thereof;
FIG. 3 is a rear view thereof;
FIG. 4 is a left side elevation thereof;
FIG. 5 is a right side elevation thereof;
FIG. 6 is a top plan view thereof; and,
FIG. 7 is a bottom plan view thereof.
